(57) CLAIM

The ornamental design for a storage box, as shown and described.

DESCRIPTION

FIG. 1 is a front, top perspective view of a storage box, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of detail “9” identified in FIG. 1;

FIG. 10 is another perspective view of the storage box, shown in an alternate position; and,

FIG. 11 is another perspective view thereof, shown in an alternate position.

The dashed broken lines in the figures illustrate portions of the storage box that form no part of the claimed design. The dash-dot-dash broken lines in FIGS. 1 and 9 depict the bounds of the enlarged views and form no part of the claimed design.
